UNITED STATES PATENT OFFICE.

JOHN F. PIERCE, OF ELIZABETHTON, TENNESSEE, ASSIGNOR OF ONE-HALF
TO JOHN M. FOLSOM, OF SAME PLACE.

DESIGN FOR AN EAVES-TROUGH HANGER.

SPECIFICATION forming part of Design No. 26,175, dated October 13, 1896.

Application filed August 24, 1896. Serial No. 603,817. Term of patent 14 years.

To all whom it may concern:

Be it known that I, JOHN F. PIERCE, a citizen of the United States, residing at Elizabethton, in the county of Carter and State of Tennessee, have invented and produced a certain new and original Design for an Eaves-Trough Hanger; and I do declare the following to be a full, clear, and exact description of the invention, such as will enable others skilled in the art to which it appertains to make and use the same.

My invention has for its object the production of a new and original design for eaves-trough hangers.

The figure in the drawing is an illustration of an eaves-trough hanger embodying my design.

The essential feature of my design consists

of the arm, formed with circular eyes *a a*, thence extending downward, forming an eye *b*, thence extending at a right angle forward, forming a loop *c*, and bent backward upon self to form a horizontal arm *d*, passing through the eye *b*, and then forming an eye *e*, thence bent downward in the form of a semi-circle *f*, and terminating in a vertical arm *g*, passing through the loop *c*.

What I claim is—

The design for an eaves-trough hanger, substantially as shown and described.

In testimony whereof I hereunto affix my signature in presence of two witnesses.

JOHN F. PIERCE.
